DESIGN FOR A DESK FILE

Joseph Burger, New York, N. Y.

Application September 5, 1945, Serial No. 121,844

Term of patent 7 years

(Cl. D74—1)

To all whom it may concern:

Be it known that I, Joseph Burger, a citizen of the United States and resident of the city and State of New York, county of Bronx, have invented a new, original, and ornamental Design for a Desk File, of which the following is a specification, reference being had to the accompanying drawing, forming part thereof.

The figure on the drawing is a perspective view of a desk file showing my new design.

The side not shown is the same as the side shown and the rear thereof is substantially the same as the front thereof.

I claim:

The ornamental design for a desk file, substantially as shown and described.

JOSEPH BURGER.
